SKIMMER FOR SWIMMING POOLS

Joseph Diemond, Simsbury, and Melvin Y. Gershman,
West Hartford, Conn., and Fred A. Ravreby, Framing-
ham, Mass., assignors to Coleco Industries, Inc., Hart-
ford, Conn., a corporation of Connecticut

Filed Feb. 7, 1969, Ser. No. 15,685

Term of patent 14 years

Int. Cl. D23—01

U.S. Cl. D23—4

FIG. 1

FIG. 2

FIG. 3

FIG. 4

FIG. 5

FIGURE 1 is a perspective view of a skimmer for swimming pools showing our design;

FIGURE 2 is a front elevational view thereof to a reduced scale;

FIGURE 3 is a side elevational view thereof on the same scale as FIGURE 2;

FIGURE 4 is a top plan view thereof on the same scale as FIGURE 2; and

FIGURE 5 is a bottom plan view thereof on the same scale as FIGURE 2.

We claim:

The original design for a skimmer for swimming pools, as shown.
